UNITED STATES PATENT OFFICE.

GEORGE BROCKINGTON, OF NEWARK, NEW JERSEY.

BRIDLE-BIT.

SPECIFICATION forming part of Letters Patent No. 466,485, dated January 5, 1892.

Application filed February 11, 1891. Serial No. 381,053. (No model.)

To all whom it may concern:

Be it known that I, GEORGE BROCKINGTON, a citizen of the United States, residing at Newark, in the county of Essex and State of New Jersey, have invented certain new and useful Improvements in Bridle-Bits; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The objects of this invention are to reduce the cost of manufacturing bridle-bits of a certain high class, to dispense with certain stops between which and the head of the mouth-piece the horse is apt to catch his lips or the 20 flesh at the ends of the mouth; to secure increased strength and a better finish, and to obtain other advantages, some of which will be referred to in connection with the description of the working parts.

25 The invention consists in the improved bridle-bit and in the arrangements and combinations of parts, substantially as and for the purposes set forth hereinafter.

Referring to the accompanying drawings, 30 in which like letters indicate corresponding parts in each of the several views, Figure 1 is a front elevation of the improved bit. Fig. 2 is an end view of the same. Fig. 3 is a plan of one of the cheek-pieces detached from the 35 mouth-piece. Fig. 4 is a detail sectional view showing the method which may be employed in uniting the mouth and cheek pieces; and Fig. 5 is a section taken on line α , Fig. 1.

In said drawings, a indicates the mouth-piece of the bit, which may be covered with rubber or other covering material or be of naked metal, and may be either rigid or of jointed sections in any ordinary manner. At the ends of said mouth-piece are vertically-perforated heads a' , adapted to receive the pivotal portions e of the rein-loop bars d of the cheek-pieces b , the said pivotal portion e extending diametrically across the rein-ring c , as will be understood. The pivoted portion 50 or pin e is in two parts, as shown in Fig. 3, both being integral with the ring c , as shown,

but separated or being provided with an opening f at the center of the ring, or in line with the longitudinal axial center of the mouth-piece. The ends of the pin-sections e 55 are preferably longitudinally forked or slotted, the slots in certain varieties of the bit allowing a limited vertical play of the mouth-piece on the said pin, which is deemed desirable. The ends of the mouth-piece at the 60 heads a' are longitudinally cored or provided with key-holes a^2 , which extend at right angles to the vertical perforations for the pin e . The bit consists of a piece of iron or steel of any shape or size adapted to be inserted between 65 the portions of the pivotal pin to limit the longitudinal movements thereof. When the keys h are driven into said pin-holes between the portions e the cheek-pieces are held securely to the mouth-piece and the bit is ready 70 for use. The key may be cast integral with the head a' , thus dispensing with holes a^2 . The pins or parts e are without shoulders or similar lateral bearings to engage outward bearings on the heads and prevent longitudinal movement; but on the contrary the said pins are allowed a limited longitudinal movement, or a movement at right angles to the longer axis of the mouth-piece, a movement 75 deemed desirable in this class of bits to allow 80 the horse to play with the cheek-piece. By dispensing with exposed shoulders there is no chance for the horse's lips being caught between the bearings and cut or injured. The key or inward bearing cast or inserted between the ends of the parts e is smaller in 85 diameter than the space between the key-bearings of said ends, and thus the cheek-piece is allowed the limited play.

The method employed in uniting the parts 90 is illustrated in Fig. 4, in which the cheek-piece is shown to be cast in a bent position or form, so that the parts e lie at angles with one another, and the head can be readily placed in position on one of them, after which 95 the other of said parts e is bent into line, the said other part passing into the opposite end of the pin-perforation. When a separate key is employed with its key-hole, the cheek-piece being straightened, as shown in Fig. 4, the two 100 portions e being thus brought into line, so that the head can be slipped on said portions and

the hole a^2 be brought into coincidence with the opening f , the key h can then be driven home and the bit be made complete so far as the metal parts are concerned.

5 While the mouth-piece may be bare metal, I prefer in finishing the said mouth-piece to cast a rubber covering around the same, and in doing so I prefer to employ dies or molds adapted to give the desired form to the rubber.

10 Having thus described the invention, what I claim as new is—

15 1. The improved bridle-bit, combining with the mouth-piece having keys or inner bearings within the heads thereof cheek-pieces having pivotal pins $e e$ arranged on opposite sides of said inner bearings and having a limited play at right angles to the axis of the mouth-piece, substantially as and for the purposes set forth.

20 2. The improved bridle-bit herein described, in which is combined a mouth-piece open at

opposite sides to allow the insertion of the pivotal pins or sections of the cheek-pieces and provided with key-holes a^2 , extending at right angles to the longitudinal centers of said pins, cheek-pieces having pivotal sections or pins separate from one another at the longitudinal axial center of the mouth-piece to admit of the pins being inserted in the mouth-piece openings from opposite sides, 30 and a key or pin secured in said key-hole a^2 and extending into the place of separation between said pins and limiting or stopping the vertical movement of said pins, substantially as set forth.

35 In testimony that I claim the foregoing I have hereunto set my hand this 10th day of February, 1891.

GEORGE BROCKINGTON.
